TRANSIT SUPPORT

Charles H. Reed, Bobtown, Pa.

Application January 23, 1950, Serial No. 140,064

1 Claim. (Cl. 248—354)

1

This invention relates to surveying instruments generally, but relates specifically to a transit stand having only one leg with an earth contact member at each end thereof for wedging between two surfaces, such as the top and floor of a mine.

One object of this invention is to provide a transit stand for use in places having an overhead surface, such as a coal mine, with only one foot to rest upon the floor of the mine, and being stabilized by a foot for contacting the ceiling of the mine, to thereby avoid the difficulty of finding three spots on the floor of suitable character to support a conventional stand.

Another object of this invention is to provide an improved telescoping structure for use as a transit stand in a mine.

Still another object of this invention is to provide a one-legged transit stand capable of supporting a surveyor's transit at any selected elevation from the floor to the ceiling of the mine.

And another object of this invention is to provide a self-adjusting foot portion for a one-legged mine transit, which foot portion will swivel to conform to an uneven footing surface.

Other objects and a fuller understanding of this invention may be had by referring to the following description and claim, taken in conjunction with the accompanying drawing, in which:

Figure 1 is a side-elevational view of a one-legged mine transit stand incorporating the features of this invention;

Figure 2 is an alternate foot portion incorporating a single point which may replace the three-pointed foot portion illustrated at the bottom of the stand when positioned as illustrated in Figure 1;

Figure 3 is a section along line 3—3 of Figure 1;

Figure 4 is a section substantially along line 4—4 of Figure 1, illustrating the cross-sectional appearance of the vernier adjustment collar only, omitting the cooperating portions of the entire post;

Figure 5 is a top view of the vertically adjustable table member and a section through one section of the post, taken as indicated along line 5—5 of Figure 1;

Figure 6 is a top view of the grip clamp and vernier adjustment members provided to longitudinally adjust the length of the post, taken along line 6—6 of Figure 1; and

Figure 7 is a vertical section taken along line 7—7 of Figure 6.

2

The drawings illustrate in detail one embodiment of a mine survey instrument made according to the principles of this invention. The illustrated embodiment comprises a post member 10 having tubular portions 11 and 12. Tubular portion 11 is dimensioned to slide into the tubular portion 12 and thereby provide a telescoping action for the post member 10. That is, the post member 10 can be extended or retracted to substantially the degree of telescoping provided by the two members 11 and 12.

In mine surveying work the floor of the mine is seldom level enough to provide a satisfactory foundation upon which to set a conventional tripod for supporting a surveyor's transit. Furthermore, there are often situations in which a rise in the mine floor limits the field of the transit because the transit cannot be raised high enough on the conventional tripod. On the other hand, in many instances it is necessary to lower the transit close to the floor in order to sight past a dip in the mine roof. The conventional transit cannot be lowered in most instances without extra help to hold the tripod feet, and often the width of the corridor in which the transit is placed is not great enough to allow sufficient spread of the transit seat.

The improved instrument of this invention provides a single post which is adapted to wedge between the ceiling and floor of the mine corridor and provide a post upon which a table 30 can be moved in substantially any position from the ceiling to the floor of the mine. The post member 10 is adapted, according to the teaching of this invention, for rapid engagement between the ceiling and the floor of the mine. A clamp 13 is provided to encircle the small tubular section 11 and clamp tightly thereto. The clamp 13 is in the form of a split collar having ears 15 thereon. A stud 16 is threadably engaged with one of the ears 15 and extends through the other ear 15 in close engagement, but is not threaded thereto. A handle 17 is provided to rotate the stud 16 and thereby pull the ears 15 together to pinch the clamp 13 tightly upon the small tubular section 11. Thus, the clamp 13 provides a block which may be moved to any selected position with respect to the small tubular section 11 and thereafter prevent movement of the tubular section 11 into the tubular section 12 further than the position of the clamp 13. Accordingly, the clamp 13 may be released and the tubular sections 11 and 12 telescoped together until the post 10 is moved into a vertical position at the place where it is desired to be set up. Thereafter, the tubular sections 11 and 12 are extended until snug con-

tact is made between the floor and the ceiling of the mine, whereupon the handle 17 is actuated to grip the clamp 13 upon the small tubular section 11 at the end of the large tubular section 12 and thereby prevent telescoping of the post member 10.

Such a snug fit is enough to prevent the post member 10 from falling of its own weight, but is not sufficiently tight to provide the rigidity desired for a transit during a surveying operation. Therefore, the clamp 13 is provided with a threaded skirt 14, and a vernier collar 18 is provided with internal threads 19 adapted to engage the threaded skirt 14. The vernier collar 18 is also provided with threads 20 adapted to engage threads 21 placed at the end of the large tubular section 12. The threads 19 and 20, as well as the threaded skirt 14 and the threads 21, are of opposite hands, and therefore rotation of the vernier collar 18 will tend to move the skirt 14 and consequently the clamp 13 away from the threads 21, and consequently the large tubular section 12. In the illustrated embodiment, the vernier collar 18 is split vertically and provided with ears 24 on both sides of the split. A stud 25, having left-hand threads on one end thereof, and right-hand threads on the other end thereof, bridges between the two ears 24. Openings, as illustrated, or slots, are provided in the ears 24, and the threaded ends of the stud 25 extend beyond the sides of the ears 24. Serrated nuts, held normally nonrotative, but adjustable, by lock members 26, are threaded upon the ends of stud 25. A handle 22 is attached to stud 25 at a position between ears 24. By swinging the handle 22 vertically with respect to the post member 10, the ears 24 may be drawn together, or released. Further, the handle 22 may be swung outwardly to a position substantially as illustrated in Figure 1, releasing the force on ears 24, and thereafter used as a lever to rotate the collar 18. Such split vernier collar has been found, in actual practice, to be better than one not split, because it can be tightened to prevent loosening by vibration, and further, the handle 22 can be swung out of the way against the post when in use. It will be seen, therefore, that after the post member 10 is manually extended into a snug fit between the ceiling and floor of the mine and the clamp 13 secured to hold the post member 10 in such snug fit, the vernier collar 18 may thereafter be rotated to further extend the post member 10 and wedge it tightly between the ceiling and floor of the mine, thereby providing the rigid support required for a transit instrument stand.

In conveyor mines, the edge of the conveyor is almost always placed on the surveyor's sight line. With the conventional tripod used by surveyors, when it becomes necessary to place a transit along such a conveyor, the entire conveyor must be shut down, and of course the mine becomes inactive. With the improved transit instrument of this invention, the post 10 is placed close beside the conveyor while the conveyor is operating, and the table 30 is swung over the edge of the conveyor. The rigid support provided for the transit by the post 10 and the small space required, will permit accurate surveying while the mine continues to operate.

Further, it is often necessary to move a survey instrument quickly to get out of the way of an approaching "trip" in a track, or mobile rubber mounted, mine. The clamp 13 may be loosened to release the post 10 almost instantly, and the

engineer can get his equipment out of the path of the "trip" in short order.

Mine surveying engineers have often had the experience of having the roof of a mine cave in on them while working. With the post 10 of this invention, additional safety is provided, not so much in supporting the mine roof, as in warning the engineer of any roof movement. The transit level will warn the engineer of any incipient movement.

It has been found that the usefulness of this improved mine survey instrument is greatly increased by the provision of pointed members to serve as opposite end feet of the post member 10. At the bottom of the post member 10, in the position illustrated in Figure 1 of the drawings, a triple-pointed end 34 is illustrated as being held in the end of the large tubular section 12 by means of a set screw 35. The triple-pointed end serves very well in most instances and provides good locking engagement with either the floor or ceiling of the mine, as the case may be, but it has been found that in many instances a single point in the form of a cone 36 may be desirable, such as is illustrated in Figure 2 of the drawings. For example, in use with buildings, it has been found that a center punch mark can be properly located, and then the point 36 placed in the mark. In this manner the improved transit instrument may be used to locate members of a structural steel construction, or equipment in the building.

It has also been found that variations in the mine floor and ceiling will often prevent good anchorage of the post 10 in the particular spot desired, if a rigid longitudinally extending point is provided, and therefore it has been discovered that a swivel foot as illustrated at the top end of the post member 10 in the position illustrated in Figure 1 will provide good anchorage regardless of the contour of the surface engaged. The swivel end is provided by a flange insert 41 held in the end of the small tubular section 11 by means of a set screw 42 as illustrated in Figure 3 of the drawings. A swivel end 43 is provided with ears 44 to fit closely over the flange insert 41. It is of course understood that the reverse situation can be provided if desired. That is, a single ear may be provided on the swivel end 43 with a double flange on the insert 41. A stud 45 is threadably engaged with one of the ears 44 and extends through the other one, and is rotatably driven by a handle 46 for tightening the ears 44 upon the flange insert 41. However, the handle 46 need not be tightened to more than a snug fit, because the force produced by the vernier collar 18 in extending the post member 10 will cause the swivel end 43 to move and compensate for the irregularity of the contact surface with respect to the longitudinal axis of the post member 10. The handle 46 need be tightened only enough to hold the swivel end 43 in the general upright position until tight wedging can be accomplished. It has been found that two pointed tips 48 held upon a yoke 47 will provide sufficient contact for the swivel end 43.

The table 30 is provided with a threaded transit collar 31 thereon to hold a transit instrument in tight engagement upon the table 30. A clamp portion 32 surrounds the large tubular section 12 and is constructed in substantially the same manner as the clamp 13. A handle 33 is provided to tighten the clamp 32 in any desired vertical position upon the tubular section 12. It has been found that a series of graduations, preferably in

tenths of a foot, along the side of the tubular portion 12, will aid the surveyor in setting the proper height of the table 30. The graduations have not been illustrated upon the tubular section 12 in the reduced scale drawings necessary to illustrate this invention.

In the use of the improved mine survey instrument illustrated and described, the post member 10 is normally set with the triple-pointed end 34 against the mine floor and the swivel end 43 in contact with the mine ceiling. Normally the extent of movement of the table 30 provided by the length of the large tubular section 12 is sufficient. However, in many instances a rise in the mine floor will necessitate raising of the transit above the height normally provided by the extent of movement available for the table 30 in the position illustrated in Figure 1. This invention provides the necessary flexibility to permit raising of the transit to the ceiling of the mine. Whenever it is found necessary to move the transit to a high position, the clamp 32 is loosened and the table 30 slipped off of the tubular section 12 and reversed in an upside-down position from that illustrated in Figure 1. Thereafter, the entire post member 10 is reversed in position to place the large tubular section 12 at the top. If it is found necessary to do so, the ends 34 and 43 may be reversed to aid in the usefulness of the post member in the reverse position. The table 30 is then operable at a high level and will raise the transit to a position to sight over any raise in the mine floor. Other useful benefits and features of this improved single-post transit stand will at once be apparent to mine survey engineers who have encountered the many problems prevailing in the surveying of mines with the conventional tripod transit stand. Further, the advantageous use of this instrument for sewer survey, tunneling, building construction, and similar environments wherein an overhead surface is available, will be readily apparent to those associated with such work.

Although the invention has been described in its preferred form with a certain degree of particularity, it is understood that the present dis-

closure of the preferred form has been made only by way of example and that numerous changes in the details of construction and the combination and arrangement of parts may be resorted to without departing from the spirit and the scope of the invention as hereinafter claimed.

What is claimed is:

A survey instrument for supporting a surveying transit comprising, a longitudinally telescoping post member including a male section and a female section, one of said sections being longer than the other when the two sections are fully extended, a friction clamp collar on the male section, means to frictionally clamp said collar upon the said male section at any selected position and block the telescoping movement of that section with respect to the female section, said collar having a threaded skirt portion, said female section having a threaded portion, said threaded portion of the female section and said threaded skirt portion of the collar having opposite hand threads, a vernier collar having first thread means to cooperate with the threaded portion on said female section and second thread means to cooperate with the threaded skirt of the collar, the post member being thereby roughly adjustable in length to fit snugly between a mine floor and ceiling and being wedged tightly in place by actuation of said vernier collar to further extend said post member, said post member having a swivel foot member on at least one end thereof, and a vertically adjustable transit table carried by said longer section.
